UNITED STATES PATENT OFFICE.

ROBERT BRUCE, OF WELLINGTON, KANSAS.

HASP-FASTENER.

1,079,390.

Specification of Letters Patent. Patented Nov. 25, 1913.

Application filed August 7, 1913. Serial No. 783,639.

To all whom it may concern:

Be it known that I, ROBERT BRUCE, a citizen of the United States, residing at Wellington, in the county of Sumner and State of Kansas, have invented a new and useful Hasp-Fastener, of which the following is a specification.

This invention relates to improvements in hasp fasteners and more particularly to a lock or seal hasp fastener.

An object of the present invention is to provide an improved form of hasp fastener, to which may be secured a seal or lock, the construction of the fastener being such that the likelihood of the seal being wrongly applied thereto will be largely eliminated.

A further object is to provide a hasp fastener especially designed for use in connection with freight car doors whereby it will be practically impossible to wrongly apply the seal thereto.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof the preferable form of the invention is illustrated, in which:—

Figure 1 is a view in elevation of a car door with my improved hasp fastener operably secured thereto. Fig. 2 is a perspective view of the hasp fastener. Fig. 3 is a sectional view taken on the line 3—3 of Fig. 2.

Referring to the drawings in which similar reference numerals designate corresponding parts throughout the several views, the hasp 4 is provided with a slot or opening 5 extending therethrough and adjacent one of the edges thereof is a raised shoulder 6, the latter being provided with an opening 7 extending what is termed transversely therethrough. The remote end of the hasp is provided with an aperture 8 extending therethrough, through which is adapted to extend a securing staple 9 as more clearly illustrated in Fig. 1.

Rigidly secured to the car wall is a base plate 10 provided with a lug 11 projecting

therefrom and which lug is provided with an aperture 12 extending transversely therethrough and the aperture 13 extending at right angles to the first mentioned aperture and what is termed longitudinally through the said lug, the terms "transverse" and "longitudinal" being used in a relative sense in order to more readily describe the openings. The lug 11 is of such size that it passes freely and at the same time snugly through the slot or opening 5 of the hasp, it being illustrated in such position in Fig. 2. The base plate 10 is provided with the apertures 14 extending therethrough, which apertures provide means whereby the said base plate may be rigidly secured to the walls of a car or other supporting structure.

The upper portion of the base plate 10 is provided with an opening extending therein and in which is secured one end of a flexible member or chain 16 the latter being rigidly secured to the pin or key 17 the upper portion 18 of the key 17 being larger than the lower portion 19 thereof so that the restricted portion 19 will fit within the restricted aperture 13 of the lug and will be limited in its movements therein by the shoulder which of necessity exists between the juncture of the portions 18 and 19. The key 17 is provided with an aperture 20 extending therethrough and positioned a distance from the shoulder between the meeting portions 18 and 19 substantially equal to the distance which the aperture 12 is placed from the top of the lug so that when the pin has assumed its final position the aperture 20 therein will align with the transverse aperture 12 of the lug and the aperture 7 of the shoulder, all of which is clearly illustrated in Fig. 3.

A pad lock or seal may be inserted through the aligned openings 12, 20, and 7 which will lock or seal the parts in their respective relations and it will be impossible to change the respective relations of the parts until the lock is removed or the seal broken. Attention is called to the fact that in order for the hasp fastener herein described to be locked in position it will be necessary for the operator to first grasp the pin 17 and hold it up out of the way while the hasp is being inserted over the lug 11. After the hasp has assumed its final position with the lug passing through the opening therein the pin 17 is passed downwardly through the restricted aperture 13

and the same will be maintained therein due to its own weight, it being noted that the pin is inserted from the top. In order for a padlock to be passed through the openings 12 and 7 it will be necessary that the pin be in its proper position or either entirely removed from the lug, either of which positions provides that after the lock or seal has passed through the said openings 10 they will prevent the hasp from becoming disengaged from the lug. Thus there will be little likelihood of a false seal being effected which with the present forms of hasp fasteners is very likely to occur.

15 What I claim is:—

1. In a hasp fastener the combination of a hasp provided with an opening extending therethrough, a shoulder adjacent the edge of said opening and provided with an aperture extending therethrough, a plate with a lug projecting therefrom adapted to extend through the opening of the said hasp, said lug provided with apertures extending longitudinally and transversely therethrough, the transverse aperture thereof adapted to aline with the shoulder aperture, and a pin adapted to extend through the said lug longitudinal opening, said pin provided with an aperture extending trans-

versely therethrough adapted to aline with the transverse openings of the lug and shoulder.

2. In a device of the class described, the combination of a hasp provided with an aperture extending therethrough, said hasp provided with a shoulder projecting therefrom adjacent one edge of said opening, said shoulder provided with an opening extending transversely therethrough, a plate provided with a lug projecting therefrom said plate adapted to project through the hasp opening, said lug provided with transverse and longitudinal openings extending therethrough, and a key with an enlarged head having an aperture extending transversely therethrough adapted to extend through the longitudinal opening of the lug with the apertures thereof in alinement with the transverse apertures of the said lug and shoulder, and flexible means for securing the said pin to the plate.

In testimony that I claim the foregoing as my own, I have hereto affixed my signature in the presence of two witnesses.

ROBERT BRUCE.
